HEATING APPARATUS

Warren H. De Lancey, Springfield, Mass., assignor to Atlantic Development Company, Inc., Springfield, Mass., a corporation of Massachusetts

Application March 5, 1948, Serial No. 13,209

2 Claims. (Cl. 122—126)

This invention relates to oil or gas fired boilers of the type particularly adapted for heating residential houses and small industrial establishments.

A principal object of this invention is to provide a boiler which, although most efficient in operation, is, at the same time, particularly designed so as to be capable of economical manufacture by modern production-line methods. In other words, the present invention contemplates a boiler, the design of which is such that the various component boiler elements may each be simply and speedily constructed by automatic machines, and thereafter assembled together in a most simple and efficacious manner, to the end that the man-hours required for such assembly are maintained at a minimum figure.

A further object of the present invention is to provide a boiler unit which is so compact that it may be completely assembled with its controls, and be transported as a factory-tested unit, to the building in which it is to be installed and operated.

Yet another object of this invention is to provide a boiler unit which, when operated as a steam vapor boiler, is particularly adapted for supplying extremely dry or superheated steam to the house heating system which is attached thereto.

With the above and other objects in view, as will hereinafter appear, the invention comprises the devices, combinations, and arrangements of parts hereinafter set forth and illustrated in the accompanying drawings of a preferred embodiment of the invention, from which the several features of the invention and the advantages thereof may be readily understood by those skilled in the art.

Fig. 1 represents an assembly view, partly in side elevation, and partly in vertical section, of a boiler in accordance with my invention.

Fig. 2 represents a fragmentary top plan view of the present boiler unit.

Fig. 3 represents a sectional view taken substantially along the line 3—3 of Fig. 1.

Fig. 4 represents a sectional view taken substantially along the line 4—4 of Fig. 1.

Fig. 5 represents, on a reduced scale, a front view of the present boiler unit.

Fig. 6 represents, on a reduced scale, a rear view of the present boiler unit.

Fig. 7 represents a sectional view taken substantially along the line 7—7 of Fig. 1.

Fig. 8 represents a perspective view of the boiler flue elements as attached to their vertically opposed header plates.

Fig. 9 represents an end elevation view of a typical boiler flue element employed in the present boiler unit.

Referring now to the drawings which illustrate a preferred embodiment of the invention, the present boiler unit is substantially cylindrical in shape, and comprises a cylindrical outside boiler wall or shell 12 which is closed at its bottom portion by means of a so-called wet base. This wet base comprises a pair of vertically spaced plates 13 and 14 which are maintained in a properly spaced position by means of a plurality of stay studs 15, 15. The peripheral edge portions of the plates 13 and 14 are connected together by means of a circular strip 16 which is appropriately welded along its top and bottom edge portions to the vertically opposed plates. The lower edge portion of the boiler shell 12 is, in turn, welded to the strip 16 thereby forming a watertight seal. The top portion of the boiler is closed over by means of a circular top plate 17 which is suitably welded to the boiler wall 12. If desired, the entire boiler unit may be incased in an insulated metal jacket, thereby to enhance the appearance of the boiler, and at the same time, to reduce the heat losses from the same.

Referring particularly to Figs. 1, 3 and 5, it is to be understood that the lower front portion of the boiler wall 12 is apertured, and has a firebox door 18 suitably secured over this apertured portion. This door 18, as may be particularly noted in Fig. 3, is lined with firebrick, or other suitable heat-insulating material 19. The door 18 and the insulating material 19 are provided respectively with horizontally disposed apertures 20 and 21 through which the usual burner nozzle may extend.

Referring particularly to Figs. 1 and 3, there is disposed inwardly of the apertures 20 and 21, a combustion chamber defined by an arcuate upstanding shell or wall 22, the forward end portions of which are welded adjacent the apertured portion of the boiler shell 12, as at 23. The bottom portion of the combustion chamber shell 22 is closed by means of a lower disk 24 which is suitably welded about its peripheral portion to the lower edge of the shell 22. The top portion of the combustion chamber shell 22 is closed over by means of a disk 25 and an L-shaped arcuate strip 26. This disk 25 has its peripheral portion welded to the top edge portion of the shell 22, while the strip 26 has its vertically disposed portion 26' welded to both the disk 25 and the forwardly extending portions of the shell 22. The horizontally disposed portion of the strip 26 is welded to the front apertured portion of the

boiler shell 12, as at 27. This combustion chamber, in conjunction with the front wall portion of the boiler shell 12, effectively seals off the combustion area from the water and steam chamber portion of the boiler as the various wall portions of the combustion chamber are welded, or otherwise suitably connected, to either the boiler shell 12 or the bottom closure plate thereof.

Mounted directly within the confines of the combustion chamber is an open topped firebox which comprises a rear wall 28 and a pair of side walls 29 and 30 which are connected to the rear wall. The forward portions of each of the side walls 29 and 30 are welded directly to the front apertured portion of the boiler shell 12, as at 23, 23. Also, the lower edge portions of the firebox walls 28, 29 and 30 are suitably welded to the bottom plate or disk 24 of the combustion chamber. Still referring to Figs. 1 and 3, it is to be understood that the usual type of oil burner unit, which is insertable within the apertures 20 and 21, is effective to direct its flame horizontally into the firebox, while a hinge plate 31 permits air to enter the firebox and thereby enhance combustion. Of course, this plate 31 will also permit a view of the interior of the firebox and thus, enables one to ascertain whether proper combustion is taking place. This plate 31 is pivotally mounted upon a pin 32 which is carried by bars 33, in turn secured upon the firebox door 18.

The combustion gases will, of necessity, pass upwardly out of the firebox, and successively through flue sections generally designated by the numerals 35, 36 and 37, so as finally to pass out through a stack connection or tube 38 which is disposed within the back portion of the boiler shell 12.

More specifically, the flue section 36 comprises a plurality of individual vertically disposed flue elements, each of which is designated by the numeral 39. Each end portion of these flues extends through an appropriately shaped aperture provided in a respective one of a pair of horizontally disposed and vertically spaced header plates 40 and 41. By welding one end portion of each flue to its associated header plate, a rigid watertight structure is formed, which is best illustrated in Figs. 8 and 9. By referring to these latter two figures, it is to be understood that each of the individual flue sections 39, 39 comprises a pair of identical corrugated steel stampings 42 and 43 which are placed together with their corrugations in phase, and then welded at their opposite side portions 44, 44 so as to form an open ended flue having a tortuous gas-conducting passageway therein. Essentially, each flue section 39 is shaped as a flattened tube, and since these flues provide tortuous gas-conducting passageways, there is no need to provide the various flue elements with auxiliary baffle plates. By thus forming each flue element in this manner, the two halves 42 and 43 thereof may be inexpensively stamped from the same die and, furthermore, since the opposite side portions, as well as the top and bottom marginal portions of the open flue, are all left in an uncorrugated condition, the flue halves may be readily welded together and to the header plates by automatic welding equipment. In this latter connection, it is to be understood that the top and bottom marginal edge portions of each flue element are secured to their respective header plate by means of a bead of welding material which is disposed

about the flue element and at the juncture of the flue element and the header plate, as at 45. As each of these flues is corrugated substantially throughout its entire length, it is clear that they all present an extremely large surface area to the boiler water which surrounds them and, thus, they function as efficient heat transfer units.

Referring particularly to Figs. 1, 4, 7 and 8, it is to be understood that the lower header plate 40 of the flue section 36 forms a cover for the above noted lowermost flue section or gas-collecting chamber 35. As may be understood by particular reference to Fig. 8, the header plate 40 is provided with a pair of depending side walls 46, 46, each of which is adapted to be welded to an apertured portion of the combustion chamber cover or disk 25, as at 47, 47. Figs. 1 and 7 disclose that the lower gas-collecting chamber 35 is completed by a pair of side plates 48, 48 each of which is welded to the opposite side portions of the header plate 40, and to the apertured portion of the top or disk 25 of the combustion chamber, as at 49. From this, it is to be understood that the flue section or lower gas-collecting chamber 35 is formed substantially as a rectangular open bottomed box, having side walls 46, 46 and 48, 48, and a top wall or cover in the form of the header plate 40. This lower gas-collecting chamber 35 functions to gather and direct the heat and combustion gases from the combustion chamber to the various individual flues 39, 39, and it is to be understood that it is almost completely surrounded by the boiler water, so that it will function as a heat transfer unit.

Referring now to Figs. 1, 4, 7 and 8, it is to be understood that the above noted top header plate 41 comprises the bottom portion of a substantially rectangular shaped flue section or upper gas-collecting chamber 37. As may be noted in Fig. 8, the header plate 41 has projecting upwardly from one side thereof, a forward wall 50, and from its opposite side portion, an inwardly inclined rear wall portion 51. These walls 50 and 51 of the header plate act respectively as front and rear wall portions of the gas-collecting chamber 37. This chamber is further defined by a pair of side plates 52, 52, each of which is suitably welded at its bottom portion to the header plate 41, and at its front and rear portions to the header plate walls 50 and 51. By referring particularly to Fig. 1, it is to be understood that the upper edge portions of the chamber walls are all welded to an apertured portion of the boiler cover plate 17, as at 53, thereby to make for a watertight chamber. By referring to Figs. 1 and 2, it will be seen that this chamber 37 is enclosed at its upper portion by means of a boiler cover 54 which is forcibly held in position by means of a bolt 55, the lower threaded end portion of which is received within a fitting 56 suitably provided upon the upper face of the header plate 41. Between the cover 54 and the top cover plate 17 of the boiler, there may be provided the usual type of gasket 57.

From the above, it is to be understood that after the combustion gases pass upwardly through the various flue elements 39, 39, they will pass into the substantially rectangular shaped upper gas-collecting chamber 37, and thereafter out through a horizontally disposed tubular stack element 38, the inner end portion of which passes through an aperture 58 provided in the rear wall 51 of the chamber 37. This stack element 38 is

suitably welded to the plate 51, as to form a watertight juncture therewith. The outer portion of the stack connection 38 passes through the boiler shell and is normally connected with a chimney.

Still referring to Figs. 1, 4 and 7, it is to be particularly understood that there is provided within the boiler cover plate 17, a riser aperture 59 which is disposed directly over the stack tube 38. Fig. 7 particularly illustrates the fact that the stack tube 38 is oval in shape, and it has its major transverse axis disposed substantially in a horizontal plane. The spacing between the riser aperture 59 and the stack tube is small, and in a preferred form of the invention, the distance between the periphery of the stack tube and the bottom portion of the riser opening is less than the diameter of the riser opening. The riser aperture 59 functions as a steam vapor egress opening whenever the present boiler is adapted to be connected with a steam vapor heating system. However, on the other hand, if the present boiler is to be employed in conjunction with a hot water heating system, a hot water riser opening 60 may be utilized. This opening 60 is provided in the forward portion of the boiler cover plate 17.

When the above described boiler unit is to be utilized in conjunction with a steam vapor heating system, it is to be understood that steam will be generated in the upper portion of the boiler. This steam will, of course, escape out of the boiler through the riser opening 59, but as above noted, the oval shaped stack 38 is positioned directly across the riser opening so that all of the escaping steam must wipe over and about the stack tube. From this it will be understood that since all of the combustion gases pass through the stack connection 38, the latter element will be maintained at an extremely high temperature, with the result that the steam wiping over this stack will be substantially superheated, and thus an extremely efficient heating medium will be supplied to a house heating system.

In order to adapt the present boiler for heating water for domestic usage, it is provided with a removable coil unit. More specifically, this coil unit comprises a plate 61 which may be removably secured over a frame 62 which surrounds an apertured portion of the rear section of the boiler shell 12. The frame 62 is suitably welded to the boiler shell 12, and is provided with a plurality of outwardly projecting bolts 63, over which the plate 61 may be mounted in the usual manner. Nuts 64, 64 secure the plate 61 forcibly against a gasket 65 which is positioned between the frame 62 and the plate 61. As may be best seen in Figs. 1 and 6, the plate 61 is provided with inlet and outlet couplings 66 and 67 which are adapted to be suitably connected to the domestic hot water system of a house. At the inner side portion of the plate 61, these couplings 66 and 67 are appropriately secured to the end portions of a single continuous coil of pipe generally designated by the numeral 68. From this, it is to be understood that the coil 68 is mounted upon the plate 61 in a manner such that the entire coil system, including both the coil and the plate 61, may be removed from the boiler unit as an integral unit. Figs. 1 and 7 particularly illustrate the fact that the coil 68 is adapted to be inserted into the boiler between the inner pair of boiler flue elements 39, 39.

Fresh water may be supplied to the present

boiler unit through either of two apertures 69, 69, and the other aperture may be employed as a drain connection. A steam or hot water return opening 70 is also provided in the rear portion of the boiler shell 12 just beneath the hot water coil unit. Referring particularly to Figs. 1 and 5, it is to be understood that water may be fed to the boiler through one of the inlet apertures 69, 69, until it rises to a level generally designated by the line 71, and thus, surrounds all of the individual flue elements 39, 39, as well as the lower gas-collecting chamber 35 and the combustion chamber. From this, it is to be seen that the present boiler unit presents an extremely large heat transfer surface area to the boiler water, with the result that a high degree of boiler efficiency results.

As illustrated in Fig. 5, various conventional instruments for indicating or controlling the 20 operation of the boiler may be mounted upon the outside of the boiler shell 12. For example, there is disclosed in Fig. 5, the usual gauge glass 72, try cocks 73, 73, pressure gauge 75, and various hot water limit controls 76 and 77.

From the above, it should also be understood 25 that the present boiler unit is particularly designed so as to be manufactured by production-line methods. For example, each of the individual boiler flue elements 39, 39 is adapted to have 30 its component side elements 42 and 43 stamped out on automatic machinery and thereafter the side portions thereof may be machine welded. Furthermore, each of the completed flue elements 39, 39 is in turn welded to its oppositely disposed 35 header plates 40 and 41, each of which, in turn, forms a portion of a respective one of the flue sections 35 and 37. Thus, the flue sections 35, 36 and 37 may be quickly and readily assembled as an 40 integral unit, and thereafter this unit may be secured by welding to the combustion chamber components, after which the boiler shell 12 may be placed about and secured to the boiler flue sections and the combustion chamber. The time required for the complete assembly of the present 45 boiler is held at a bare minimum, while at the same time, the efficiency of the boiler is not sacrificed for the simple reason that the novel flue sections 35, 36 and 37, along with the particular arrangement of the stack and riser connections, 50 function as extremely efficient heat conducting means.

I claim:

1. A heating apparatus of the steam-producing type comprising, a boiler including a vertically disposed shell, top and bottom closure plates, a combustion chamber and a combined water and steam chamber formed respectively within the bottom and upper portions thereof, said top closure plate having a vertically disposed steam riser opening therein, a box-like gas-collecting chamber disposed within the water and steam chamber and adjacent the top closure plate so as to be surrounded partially by steam vapor, a substantially horizontally disposed stack tube connected with said gas-collecting chamber and extending therefrom through said water and steam chamber and out through the boiler shell, said stack tube passing directly beneath and across the steam riser opening and having its outer periphery spaced below the bottom of the riser opening a distance less than the width of the riser opening so that substantially all of the escaping steam will wipe over and about said stack tube, and a plurality of individual hollow gas-conducting flue elements connected with the

7
bottom portion of said gas-collecting chamber and depending downwardly therefrom through said water and steam chamber for connection with said combustion chamber.

2. A heating apparatus of the steam-producing type comprising, a boiler including a vertically disposed shell, top and bottom closure plates, a combustion chamber and a combined water and steam chamber formed respectively within the bottom and upper portions thereof, the top closure plate having a vertically disposed steam riser opening therein, a box-like gas-collecting chamber disposed within the water and steam chamber and adjacent the top closure plate so as to be surrounded partially by steam vapor, a substantially horizontally disposed oval shaped stack tube having its major transverse axis disposed substantially in a horizontal plane, said stack tube being connected with said gas-collecting chamber and extending therefrom through said water and steam chamber and out through said boiler shell, said stack tube passing directly beneath and across the steam riser opening and having its outer periphery spaced below the bottom of the riser opening a distance less than the width of the riser opening so that substantially all of the escaping steam will wipe over

5
and about said stack tube, and a plurality of individual hollow gas-conducting flue elements connected with the bottom portion of said gas-collecting chamber and depending downwardly therefrom through said water and steam chamber for connection with said combustion chamber.
